UNITED STATES PATENT OFFICE.

BYRON JACKSON, OF SAN FRANCISCO, CALIFORNIA.

CENTRIFUGAL PUMP.

SPECIFICATION forming part of Letters Patent No. 440,252, dated November 11, 1890.

Application filed March 10, 1890. Serial No. 343,350. (No model.)

To all whom it may concern:

Be it known that I, BYRON JACKSON, of the city and county of San Francisco, and State of California, have invented certain Improvements in Centrifugal Pumps; and I hereby declare the following to be a true specification and description of the same, reference being had to the accompanying drawings and the letters of reference thereon.

10 This invention relates to centrifugal pumps, especially to those wherein the wheels revolve in a horizontal plane, and intended for pumping from mines or pits.

It consists in sealing the packing-glands and 15 inlet-pipes against the entrance of air, and thus insure perfect suction to the atmospheric limit; also, in the manner of constructing and arranging the packing-glands of such pumps either vertical or horizontal to secure their 20 alignment and true adjustment, and in other features, to be hereinafter more fully explained in connection with the drawings.

The objects of my invention are to guard 25 against the entrance of air around the spindles of centrifugal pumps when the suction level varies, as in the case of drawing from tubular wells or other varying sources; to secure more complete lubrication of the bearings of the pump-spindles, and a convenient adjustment 30 of such packing-glands by means of a single screw; also, balance the wheel and shafting by the pressure of the column of water in the pipes, and to dispense with bearings beneath the pump-wheels, so that all details, including 35 the suction-pipes, will be removable from the top.

The drawing represents a vertical section through one of my improved pumps as they are constructed for use in wells or pits.

40 A is the main casing, volute in form.

B is the wheel or revolving piston, and C the driving shaft or spindle.

D D are suction-inlets through which the water enters.

45 E is the discharge-pipe.

F is a packing-gland to prevent the entrance of air, and G G' are bearings for the driving-spindle.

50 H is a chamber surrounding the packing-gland F, and is connected to the discharge-pipe E by means of the small pipe I.

J is a removable plate permitting access to

the chamber H for adjusting the gland F and for inspecting or removing the fibrous packing at K.

55

These pumps being intended especially for use in pits and wells, or at low levels where the bottom is not accessible, the suction-pipes as well as all other details are placed on top above the main casing, which rests on a sole 60 plate or frame at the bottom of a pit, as shown.

To avoid bearings for the main spindle C below the wheel B, I place two long substantial bearings G G' above the wheel, and between these interpose a packing-gland F, 65 which, in addition to its function of holding and compressing the packing at K, also constitutes a bearing for the spindle, thus dispensing with a bearing below the wheel, which has been heretofore necessary. The packing-gland at F, around the spindle C, is not enough to guard against the entrance of air when the suction height is increased by the water falling in sumps or wells, and the inward pressure is thus increased. To guard against this, I 70 surround the stuffing-box and gland with a close chamber H, and then connect this chamber with the discharge-pipe E by means of a small pipe I, as shown. The chamber H being thus filled with water as soon as the pump 80 starts, any leak around the fibrous packing at K is supplied by water and no air enters. At the same time the pressure in the chamber 75 H forces the water into the gland F and upper bearing G', carrying off any heat generated, 85 and providing efficient lubrication. When the pump is driven without being charged, as in the case of starting, the cup at M being supplied with oil provides efficient lubrication until the chamber H is filled with water and 90 the air expelled. The spindle or shaft C, to which power is applied, can extend up to the surface of the ground by means of connected shafts, or power can be applied by any of the well-known methods in such cases.

95

O is a flange on the pump, fitted to the case A, of suitable diameter to balance the shafting and attachments by the difference of area, receiving pressure of water on the lower and upper side of the wheel B. The pressure is 10 relieved inside of the flange O by a hole P through the runner connecting with the suction-inlet. By making this flange O of suitable proportions to the inlet the shafting can

be balanced by the water-pressure, relieving the shaft C of end-thrust in either direction.

The suction-inlets D are made double, so that in drawing water from wells connections 5 can be made to one or more wells at each side, and in case of drawing from a single well one of these inlets is closed by a plate.

What I claim as new, and desire to secure by Letters Patent, is—

- 10 1. In a centrifugal pump, in combination, a hollow chamber or casing A, arranged horizontally, vertical bearing G, surmounting the said chamber or casing and surrounded with a housing, suction inlet or inlets D, outside said bearing G and communicating with the casing A, a horizontal wheel or piston B, a vertical revolving shaft C, vertical upper bearing G', separated from the bearing G, housing around 15 said upper bearing, and a vertical packed gland F between the bearings G G' and surrounded by suitable housing, substantially as described.
- 20 2. In a horizontal centrifugal pump, in combination, a horizontal hollow chamber or casing A, vertical bearing G, surmounting the said chamber or casing A, suction inlet or inlets D, outside said bearing G and commu-

nicating with the casing A, a horizontal wheel or piston connected with a vertical revolving shaft C, vertical upper bearing G', separated 30 from the bearing G, vertical housings around the bearings G G', annular chamber H, connecting the upper with the lower part of the housing, a vertical packed gland F between the bearings G G', pipe I, and discharge-pipe 35 E of the casing of the pump, substantially as described.

3. In a horizontal centrifugal pump, in combination, a horizontal hollow chamber or casing A, horizontally-revolving wheel or piston B, vertical shaft C, separated vertical bearings G G', packed gland F, having a suitable vertical housing, chambered flange O on the chamber A, and passage or passages P in the hub of the wheel or piston and in communication with its discharge arms or passages and with the chamber formed by the flange O, substantially as described.

In testimony whereof I hereunto affix my signature in the presence of two witnesses.

BYRON JACKSON.
